UNITED STATES PATENT OFFICE

2,539,908

MULTIPLE TEMPERATURE REFRIGERATING SYSTEM

John C. Jenkins, Minneapolis, Minn., assignor to Seeger Refrigerator Company, St. Paul, Minn.

Application May 19, 1948, Serial No. 27,860

7 Claims. (Cl. 62—8)

1

My invention relates to an improvement in refrigerating system wherein it is desired to provide a refrigerating apparatus of the multiple temperature type.

The object of the present invention resides in the provision of a refrigerator having compartments to be maintained at different temperatures and to provide an efficient system for supplying refrigerant to cool the different compartments. A separate coil is provided for each compartment and the coils are connected in such a manner as to cause the system to operate economically.

A feature of the present invention lies in the provision of a refrigerator system having two evaporator coils which are supplied with refrigerant through twin capillary tubes connected to a common liquid line. The length of capillary used for each coil is calculated to produce the desired restriction and consequently the proper feed.

A feature of the present invention lies in the provision of a pair of capillary tubes fed from a common liquid line to deliver refrigerant to a pair of evaporator coils. A relatively higher suction pressure is maintained in the high temperature evaporator coil by use of a pressure differential valve located at the outlet of the high temperature evaporator coil. The pressure differential valve is connected to the low temperature coil at a point intermediate the ends thereof. As a result the feed to the colder evaporator coil is increased at this point mid-way between the ends of the colder coil.

A feature of the present invention lies in the provision of a multi-temperature refrigeration system having a pair of evaporator coils, a pair of capillary tube supplying refrigerant to these coils, and a refrigerant return line in heat exchange relation with the capillary tubes. The suction line from the common accumulator through which all refrigerant from both coils passes is in heat exchange relation with the liquid line supplying refrigerant to the coils to increase the efficiency of the system.

These and other objects and novel features of my invention will be more clearly and fully set forth in the following specification and claims.

In the drawing forming a part of my specification, the drawing diagrammatically illustrates a refrigerant system embodying the features of my invention.

The refrigerant system may be used on a two temperature refrigerator of any desired type, the invention herein lying in the system itself rather

than in the construction of the refrigerator details.

The system A includes a motor compressor unit 10 which is provided with a refrigerant inlet 11 and a refrigerant outlet 12. The outlet 12 is connected to the condenser 13 in which the gaseous refrigerant is liquified. The condenser 13 is connected by a liquid line 14 to a pair of capillary tubes 15 and 16. Thus the liquid refrigerant is allowed to flow through the two capillary tubes 15 and 16 which are of proper length to produce the desired feed into each of the evaporator coils.

An evaporator coil 17 is connected to the capillary tube 15 and a second evaporator coil 19 is connected to the capillary tube 16. The coil 17 is designed to comprise the low temperature coil and is held at proper temperature to produce a temperature of approximately zero degree within the low temperature compartment 20. The coil 19 is located within a relatively high temperature compartment 21 and is designed to hold the temperature within this compartment at approximately 40 degrees.

The coil 19 is provided with a pressure differential valve 22 at its outlet end. The pressure within the coil 19 is held relatively high and may be for example thirty pounds per square inch. The differential valve 22 allows a greater expansion of the refrigerant and the coil 17 is maintained at a relatively low pressure such as for example a suction pressure of six pounds per square inch. A similar suction pressure is provided in the common suction line.

The coil 17 is fed at its inlet end by the capillary 35 and a second connecting conduit 23 connects the outlet of the pressure differential valve 22 to the coil 17 at a point approximately mid-way between its inlet and outlet ends. Thus the last portion of the evaporator coil 17 contains both the refrigerant fed to the coil 17 by the capillary tubes 15 and also the refrigerant fed through the coil 19 and pressure differential valve 22 from the capillary tube 16. The outlet of the low temperature coil 17 is connected as indicated at 24 to an accumulator 25 of suitable design.

The outlet of the accumulator 25 is connected by a common connection 26 to the inlet 11 of the motor compressor 10. The suction line 26 extends in double heat exchange relation with the capillary tubes 15 and 16 leading to the two coils. This feature adds to the economy of the system by tending to reduce the temperature of the refrigerant as it passes through the capillary tubes 15 and 16.

My refrigerator system has been found effi-

cient and effective for its intended purpose and produces a well regulated and smooth flow of refrigerant through the system. I have found that both coils can operate to maintain their respective compartments at substantially the desired temperature. Suitable thermostatic control, not illustrated in the drawings, is provided to actuate the motor compressor at the necessary times so as to produce the desired temperatures.

In accordance with the patent statutes, I have described the principles of construction and operation of my refrigerating system, and while I have endeavored to set forth the best embodiment thereof, I desire to have it understood that obvious changes may be made within the scope of the following claims without departing from the spirit of my invention.

I claim:

1. A refrigerating system including a refrigerant circulating means, a condensing means for condensing the refrigerant, a pair of capillary tubes connected to said condenser to receive liquid refrigerant therefrom, a pair of evaporator coils connected to said capillary tubes, the end of one of said coils connected to a mid-point of the other coil, a common return line from the end of said other coil to the refrigerant circulating means, and a pressure differential valve between the end of said one coil and the mid-point of said other coil.

2. The structure described in claim 1 in which the common return line is arranged in heat transfer relation with said capillary tubes.

3. The structure described in claim 1 and including an accumulator in said common return line.

4. The structure described in claim 1 and in-

cluding an accumulator in said common return line and in which the common return line is in heat transfer relation with said capillary tubes.

5. A refrigerating system including a refrigerant compressing and circulating means, a condenser for condensing the refrigerant circulated, a pair of capillary tubes connected to said condenser to receive liquid refrigerant therefrom, a coil operating at a relatively high temperature connected to one of said capillary tubes and a coil operating at a relatively low temperature connected to the other of said capillary tubes, a connection between the outlet end of the high temperature coil and a mid-point of the low temperature coil, a pressure differential valve in said connection, and a common return line from the outlet end of said low temperature coil to said compressor and circulating means.

6. The structure described in claim 5 in which the common return line is in heat transfer relation to said capillary tubes.

7. The structure described in claim 5 in which the capillary tubes are varied in length to produce the proper refrigerant flow to each of said coils.

JOHN C. JENKINS.
